UNITED STATES PATENT OFFICE.

WILLIAM M. FOX, OF LEBANON, PENNSYLVANIA.

BULB, FUSE, AND LICENSE-CARD HOLDER.

Application filed June 16, 1924. Serial No. 720,410.

To all whom it may concern:

Be it known that I, WILLIAM M. Fox, a citizen of the United States, residing at Lebanon, in the county of Lebanon and State of Pennsylvania, have invented certain new and useful Improvements in Bulb, Fuse, and License-Card Holders; and I do declare the following to be a full, clear, and exact description of the invention, such as will enable others skilled in the art to which it appertains to make and use the same.

The principal object of my invention is to provide a simple, inexpensive, compact and convenient device for carrying replacement bulbs and fuses for use on automobiles, provision being also preferably made for holding the driver's license card.

In carrying out the above end, further objects are to provide unique means for holding the bulbs in place, to make novel provision for yieldably retaining the license card, to provide simple means for holding the fuses, and to provide an exceptionally simple and inexpensive, yet an effective casing structure for containing the bulbs, fuses and card.

With the foregoing in view, the invention resides in the novel subject matter herein-after described and claimed, the description being supplemented by the accompanying drawings.

Figure 1 is a perspective view of a device constructed in accordance with my invention.

Figure 2 is a vertical longitudinal sectional view with the upper section of the casing swung open.

Figure 3 is a horizontal sectional view on line 3-3 of Fig. 2.

Figure 4 is a similar view on line 4-4 of Fig. 2, but looking upwardly.

Figures 5 and 6 are vertical transverse sectional views as indicated by lines 5-5 and 6-6 of Fig. 2.

Figure 7 is a plan view of the blank from which the lower section of the casing is formed.

Figure 8 is a similar view of the blank from which the upper casing section is constructed.

In the drawings above briefly described, the numerals 1 and 2 designate respectively the lower and upper sections of a sheet metal casing, and 3 designates an elongated rectangular base preferably formed of wood, this base being carried within the lower casing section 1. The base 3 is formed with a

plurality of vertical openings 4 through which the usual plugs 5 of a plurality of bulbs 6, may be inserted as shown clearly in Figs. 2 and 5, the walls of said openings being formed with vertical grooves 7 through which the usual lateral studs 8 of the plugs 5, are movable. The lower side of the base 3 is also by preference formed with longitudinal grooves 9 between the openings 4, to receive the studs 8 after the plugs 5 have been inserted through the openings 4 and turned a quarter of a revolution. Secured under tension to the lower side of the base 3 and extending across all of the openings 4, is a flat elastic strip 10 which is preferably formed of rubber, said strip being secured to the base at its ends and between the openings 4 by staples or the like 11. Normally, when there are no bulbs in the holder, the strip 10 assumes a truly horizontal position, but when the plug 5 of a bulb is inserted downwardly through an opening 4, the lower end of said bulb and its contact depress the strip 10 as shown in Fig. 2, placing it under additional tension. Then, when the bulb and plug are turned to move the studs 8 out of alignment with the grooves 7, the tension of said strip will effectively hold the bulb and its plug in the position to which it has been turned. If the base be provided with the grooves 9, and it preferably is, the studs 8 are held in these grooves by the tension of the strip 10. To remove a bulb, it is simply necessary to depress it to some extent and turn it until the studs 8 again align with the grooves 7, whereupon the bulb may be easily withdrawn for use.

Provision is made for holding a plurality of fuses 12 upon the base 3, between the bulbs 6, such provision being preferably in the form of a single elastic strip 13 secured at intervals to the base by staples or the like 14, providing flexible, elastic loops 15 through which the fuses may be readily inserted and by which they are normally held. It will be seen however that any fuse may be easily removed when desired.

The rear edge of the base 3 is preferably spaced to some extent from the back wall of the lower casing section 1, to provide a space 16 into which the lower end of the driver's license card 16', may be inserted, and to yieldably hold the card in place, a strip of rubber or the like 17 is secured by suitable fasteners 18 to the lower side of said base, said strip projecting slightly

beyond the rear edge of the base, as indicated at 19 in Figs. 4, 5 and 6. This projecting portion of the strip 17 downwardly bowed to some extent by insertion of the 5 card 16 and it will effectively hold said card in place, yet will permit it to be easily removed whenever necessary.

The preferred casing structure is shown, in which the lower section 1 comprises a 10 relatively high back wall 20, a bottom wall 21 integral with and bent forwardly from said back wall, under the base 3, a comparatively low front wall 22 integral with and bent upwardly from the bottom wall 21 at the 15 front edge of the base 3, and a pair of triangular end walls 23 which are integral with and bent forwardly from the back wall 20. Screws or other fasteners 24 pass through the front and end walls 22 and 23 and se- 20 cure them to the edges of the base 3, as well as securing the latter within the casing, in upwardly spaced relation with its bottom 21. It will be seen that this construction requires only the stamping and bending of a metal plate and requires no soldering 25 or the formation of other seams.

The upper casing section 2 has a top plate 25. A relatively wide front wall 26 is bent downwardly from and is integral with the 30 top wall 25, and two end walls 27 are integral with and bent rearwardly from the front wall 26. These end walls and the end walls 23 are preferably of the triangular shape shown. A pair of ears 28 are integral with and bent downwardly from the ends of the top wall 25 and they lie against the outer sides of the end walls 27 to hold the latter against outward springing, said walls 27 being disposed against the outer 40 faces of the walls 23 to hold them against any inward movement. Combined pivots and fasteners 29, such as ordinary rivets pass through the ears 28 and the end walls 23 and 27, and they may well have washers 45 30 on their inner ends.

Attention is directed to the fact that in constructing the upper casing section 2, only the stamping and bending of one piece of sheet metal is required, and the construction 50 is such that the combined pivots and fastener 29 hold the several walls of said section in rigid relation with each other as well as pivoting the upper casing section to the lower section. Thus, an unusually simple and 55 inexpensive structure is provided requiring no soldering or other seaming.

In order to yieldably hold the two casing sections in relatively closed positions, as seen in Figs. 1 and 5, the wall 22 is preferably 60 stamped to provide a rib 31, and the lower edge of the wall 26 is bent at 32 to form an internal groove which is adapted to snap over the rib. This formation and the friction existing at the pivots of the casing sec- 65 tions, will effectively hold said sections in

the relative positions shown in Fig. 1, yet will permit easy opening of the upper section when necessary.

It will be seen from the foregoing that an exceptionally simple and inexpensive device 70 has been provided for carrying out the objects of the invention, and it will also be understood that certain features of the invention need not be restricted to the exact uses herein set forth. Moreover, while I have 75 described and claimed the construction as if it were used in the vertical position shown for instance in Figs. 1, 5 and 6, it will be clear that it might be used in some other position if desired. 80

Excellent results have been obtained from the details disclosed and they are therefore preferably followed, but within the scope of the invention as claimed, numerous modifications may, of course, be made. 85

I claim:

1. A holder for automobile light bulbs comprising a base having a plurality of openings through which the usual plugs of the bulbs are insertable, opposed sides of said 90 openings having grooves through which the common lateral studs of the bulb plugs are movable, and an inherently elastic strip extending across the lower ends of said openings and secured to the base at intervals, said 95 strip being adapted to engage the bulb plugs and yieldably hold the above named studs against the lower side of the base when the plugs are inserted through the openings and turned to move the studs out of alignment 100 with the aforesaid grooves.

2. A device of the class described comprising a casing, a base secured in said casing in spaced relation with its bottom and having a plurality of openings through 105 which the usual plugs of light bulbs are insertable, opposed sides of said openings having grooves through which the common lateral studs of the bulb plugs are movable, and an inherently elastic strip between the 110 base and the casing bottom, said strip extending across the lower ends of said openings and being secured to the base at intervals, said strip being adapted to engage the bulb plugs and yieldably hold the above 115 named studs against the lower side of the base when the plugs are inserted through the openings and turned to move the studs out of alignment with the aforesaid grooves.

3. A device of the class described comprising a casing, a base secured in said casing in spaced relation with its bottom and one side wall, the space between said side wall and base being adapted to receive the lower edge portion of a card, and an elastic 125 strip secured to the lower side of said base and projecting slightly therefrom toward said side wall to frictionally engage and hold the card.

4. A device of the class described com- 130

prising a rectangular base, a back wall contacting with and rising from the rear edge of said base, a bottom integral with said back wall and bent forwardly therefrom under the base, a front wall integral with said bottom and bent upwardly therefrom in contact with the front edge of the base, a pair of end walls integral with said back wall and bent forwardly therefrom against the ends of the base, and fasteners passing through said front and end walls into the base to secure said walls in fixed relation and to secure said base in place.

5. A device of the class described com-

prising a lower casing section; an upper casing section comprising a top wall, a front wall integral therewith and bent downwardly therefrom, end walls integral with said front wall and bent rearwardly therefrom, and ears integral with the ends of said top wall and bent downwardly against the outer sides of said end walls; and combined pivots and fasteners passing through the ears and end walls and through the ends of the lower casing section.

10. In testimony whereof I have hereunto affixed my signature.

20. WILLIAM M. FOX.
